(57) **CLAIM**

The ornamental design for a “portable satellite station combination,” as shown and described.

DESCRIPTION

FIG. 1 is a perspective view of a portable satellite station in a closed position.

FIG. 2 is a top plan view of the closed portable satellite station combination of FIG. 1.

FIG. 3 is a bottom plan view of the closed portable satellite station combination of FIG. 1.

FIG. 4 is a front view of the closed portable satellite station combination of FIG. 1.

FIG. 5 is a rear view of the closed portable satellite station combination of FIG. 1.

FIG. 6 is a right side view of the closed portable satellite station combination of FIG. 1.

FIG. 7 is a left side view of the closed portable satellite station combination of FIG. 1.

FIG. 8 is a perspective view of the portable satellite station combination of FIG. 1 in an open position.

FIG. 9 is a top plan view of the open portable satellite station combination of FIG. 8.

FIG. 10 is a bottom plan view of the open portable satellite station combination of FIG. 8.

FIG. 11 is a rear view of the open portable satellite station combination of FIG. 8.

FIG. 12 is a front view of the open portable satellite station combination of FIG. 8.

FIG. 13 is a right view of the open portable satellite station combination of FIG. 8; and,

FIG. 14 is a left view of the open portable satellite station combination of FIG. 8.
